DISCHARGE LAMP

Edmund A. Reuter, East Orange, and Dewey D. Knowles, Verona, N. J., assignors to Westinghouse Electric & Manufacturing Company, East Pittsburgh, Pa., a corporation of Pennsylvania

Application August 13, 1941, Serial No. 406,580

9 Claims. (Cl. 176—122)

This invention relates to discharge lamps, and more particularly to lamps adapted for sterilizing purposes.

As is known, sterilizing lamps are employed in various places, such as in refrigerators, for which purpose such lamps must be operable from the usual domestic source of supply, generally 110 volts. Provision is necessary not only to operate the lamp at line voltage, but to start it promptly with that available voltage. Ultra-violet radiation, especially that of short wavelength at about 2537 Angstrom units, which is the most highly bactericidal, is generated most effectively or profusely under favorable conditions of pressure and temperature in the lamp. It has also been found necessary in lamps of the character indicated, to include a ballast in the electrode circuit, and this has introduced physical and thermal difficulties in manufacture and use.

An object of the present invention is to make a satisfactory sterilizing lamp for low-voltage operation.

Another object of the present invention is to maintain the lamp temperature at the point which gives the proper mercury vapor pressure for the most efficient generation of ultra-violet radiations.

Another object of the present invention is to utilize as little heat as possible and to apply it effectively for the purpose stated.

A further object of the present invention is to incorporate the ballast resistance within the lamp envelope.

A still further object of the invention is to utilize the ballasting resistance for a secondary purpose of producing beneficial heat for maintaining the desired lamp temperature.

Yet another object of the invention is to overcome presence of a dark spot or shadow longitudinally between electrodes intercepting the radiation.

Other objects include provision of a substantially symmetrical construction; to increase sturdiness, lower cost, secure simplicity, and employ a heating-ballast in which the heat is generated at the portion of the resistance curve which gives a small change in temperature for a relatively large change in volume.

Still further objects will appear to those skilled in the art as the description progresses, both by direct statement thereof and by implication from the context.

In the accompanying drawing, wherein like numerals of reference indicate similar parts

throughout the several views, and wherein the invention is disclosed in a few only of the many possible physical embodiments;

Figure 1 is a longitudinal sectional view of a discharge lamp embodying features of our invention;

Figures 2 and 3 are cross-sectional views thereof on lines II—II and III—III respectively;

Figure 4 is a cross-sectional view similar to Fig. 3, illustrating a modification of conductors and their mounting;

Figure 5 is an abbreviated longitudinal sectional view similar to Fig. 1, showing a modified construction of ballast-resistor and electrode connection;

Figure 6 is a cross-sectional view taken on line VI—VI of Fig. 5; and

Figure 7 is a still further modified construction of resistor and electrode connections shown in elevation on the flare or stem of a lamp.

In the broad general aspect of use, construction of and gaseous medium involved in the present invention, reference may be had to patent of Robert F. James (issued in consequence of application S. N. 734,620), for radiating apparatus. The present invention utilizes an elongated vitreous envelope 10, opposed electrodes 11, 11 near opposite ends thereof, and a gaseous medium with a mercury vapor content, as broadly specified in that patent.

The envelope preferred, however, is one which is elongated and having a screw-threaded base 12 at one end for standard connection through a usual socket (not shown) to the source of potential, and having its end opposite the base formed as a rounded closure in accord with the more usual lamp practice. The character of glass is selected for its beneficial transmission of the desired ultra-violet radiations, for which purpose it may preferably comprise borosilicate glass free from iron and identified in the trade as "high transmission glass" or "Corex D." Said envelope is shown provided at the base end with a re-entrant stem 13 through which are sealed conductors for the current supply, one from the screw threaded conductive portion of the base and another from the central bottom tip 14 of the base which is insulated from the said threaded portion.

Turning attention specifically to Figures 1, 2 and 3, the lamp there shown provides a central conductive rod or wire 15 sealed into the press 16 of stem 13 and in continuation of connection 17 which extends downward through the stem where it is in series with a ballast resistance 18

which is, in turn, in series with a final connection 19 to the bottom tip 14 of the base. The far end of the central conductive rod or wire 15 extends to the proximity of the rounded outer end of the lamp envelope and is there braced in position by a suitable support 20 with respect to the side walls of the envelope. Said support 20 shown comprises a generally circular mica disk crosswise of the rod near its end, said disk having a central eyelet 21 gripping the disk and slidably upon the rod. At outer peripheral parts of the disk are applied spring tabs 22 resiliently engaging the side walls of the envelope.

Longitudinally surrounding the said rod 15 for the greater part of its length, is an insulative sleeve 23 of tubular formation, preferably shoulered, as at 24, near its end toward the stem with a reduced neck from said shoulder downward toward the stem. Around this neck is an insulating collar 25 which extends substantially from the shoulder to the press end of the stem 13.

Between the shoulder 24 of the sleeve 23 and juxtaposed end of said collar 25 is situated a transverse disk-like end wall 26 of a cylindrical electrode 11 which extends upwardly away from said end wall and stem co-axial with and around said rod 15 and sleeve 23 for a portion of the lengths of those parts. The inner diameter of the electrode is considerably greater than the outer diameter of the sleeve thereby providing a material opening or gap between electrode and sleeve and with the far end of the electrode open. A similar electrode 11 is mounted at the far end of the sleeve, in this instance the disk-like end wall 26 of the electrode engaging against the end of the sleeve and secured thereagainst by a metallic conductive collar 27 carried therebeyond on the protruding end portion of the rod. The near end of the far electrode 11 is also open and its cylindrical wall spaced from the sleeve, so that the open end of the two electrodes face each other, but are spaced quite a distance apart longitudinally, representing the glow discharge distance to be effected when the lamp is in operation. The inner circumferential wall of both electrodes are preferably electron emissive, as by having a coating 28 thereon of emissive material, such as strontium, barium and calcium oxides.

The electrode 11 next the press is, as shown and described, insulated from the central rod, and to connect it electrically with the other side of the power supply, is shown as having a lug 29 at its lower closed end depending towards the stem and welded or otherwise secured to a conductor 30 projecting upward from the press and bent at its upper end to cross said lug. The lower end of conductor 30 sealed in the press has a connection 31 to the screw base 12.

The envelope has a tubulation 32 enabling the usual evacuation to be effected, after which appropriate gas charging is effected, including introduction of desired amount of mercury for production of mercury vapor. The usual gaseous medium may be any one or combination of noble gases, such as argon, neon, and the like. Introduction of mercury may be by including the same in a pellet 33, here shown as hung from the conductor 30 next the stem where it may be conveniently flashed by a high frequency current applied for the purpose, all of which is more fully explained in co-pending application of co-inventor herein, Edmund Reuter, S. N. 399,059, filed June 21, 1941.

A feature of the present invention is provision of means for initiating the discharge automatical-

ly and without moving parts and at normal operating voltage. As a physical fulfillment of this objective, we provide trigger members in the several views, the same being shown in Figures 1 and 3 as strips 34, 35 of electrically resistive material on diametrically opposite sides of the insulative sleeve 23 extending longitudinally thereof. One of these strips, as 34, is electrically and physically connected with the electrode 11 nearest the press and extends therethrough out of the open end thereof, along the sleeve, and terminates on said sleeve somewhat within the open end of the far electrode. Similarly strip 35 is electrically and physically connected with far electrode 11 and extends therethrough out of the open end thereof, along the sleeve toward the press and into the open end of the near electrode, terminating somewhat within the same.

Initial application of potential of voltage sufficient to maintain glow discharge between the electrodes when once the discharge is started, is not sufficient to ordinarily initiate the discharge directly from one electrode to another separated proper operating distance. However, by use of trigger means such as the resistive strips or members 34, 35 coming to closer association with the electrodes within minimum break-down voltage distance of the gaseous atmosphere, an ionizing discharge between said electrodes and trigger members will occur, and by virtue of the ionized atmosphere, the glow discharge between electrodes 11, 11 then follows.

Attention is called to the fact that the glow discharge from one electrode to the other entirely surrounds the intervening portion of sleeve 23, and consequently no shadow is cast by the conductor resultant from its passage to the far end of the lamp. While the provision of the central conductor and sleeve produces a symmetrical construction, full advantage thereof without the resistive trigger members present is not obtained, due to the fact that the starting voltage is then too high because of charges collecting on the central glass spacer or sleeve 23 as well as on the envelope wall. By our construction, however, we overcome the detrimental effects by inclusion of the resistive trigger members or strips. Thus we gain the advantages of a symmetrical construction with its lower cost of material, its simplicity and consequent greater ease of assembly and reduction of labor cost, its greater sturdiness and its elimination of dark spots or shadows in the ultra-violet output.

There are various ways of providing trigger members on the electrode. For instance, as shown in Figures 1, 2, 5 and 6, they may be painted as narrow bands or strips of resistive material of suitable consistency and thickness which will adhere and dry in place. Or these same views may be equally illustrative of preformed strips of resistive material applied by adhesion longitudinally of the insulative sleeve.

Again, resistive trigger members 34', 35' may be included or partly included in preformed grooves 36 in the outer surface of an insulative sleeve 23' of Fig. 4, with the lamp otherwise formed and operated as above described. While also, the said trigger members may be formed in place by painting or the like, as previously described, aided by the grooves to receive the then plastic material, yet we have chosen to illustrate preformed resistive wire-like members 34', 35' in said grooves, held therein by adhesive or otherwise.

It is a desirable feature of a lamp of the character indicated, to maintain the lamp tempera-

ture at the point which gives the proper mercury vapor pressure for the most efficient generation of ultra-violet radiation, and to provide a series ballasting resistance. In the above description the series ballasting resistance 18 is shown within the base. However, for rendering the base applying operation more simple, and for utilizing the ballast resistance to also more effectively obtain a desired temperature control in the lamp, it is preferred to incorporate the same within the envelope, as shown in modified constructions of Figures 5-7.

Referring now to Figures 5 and 6, the parts of the lamp structure necessary for illustration of the modified parts over the general structure of Figures 1 to 4 are there shown. This showing modifies the stem structure only to the extent that the central rod 15" is sealed in the press without an electrical connection therefrom through the stem. Instead, a lead-in connection 17" direct from the base tip is provided to make connection with a ballast resistance and heater element 18" extending longitudinally of a passage 37 parallel to and offset from rod 15". Said offset passage 37 extends the length of the sleeve 25 enabling the far end of the heater-ballast element 18" to extend to the end wall 26 of the far electrode and be physically and electrically attached thereto. The lower end of the heater-ballast wire 18" protrudes from a side opening 38 in collar 25" and is attached to aforementioned connection 17". In this showing, therefore, current is carried from tip 14 through connection 17" and heater-ballast 18" to the far electrode 11 instead of through rod 15 of the previously described assembly. Current to the near electrode 11 in both arrangements is through connection 31, conductor 30 and lug 29. Envelope enclosure, basing, gaseous medium, mercury vapor and starting trigger members for the construction of Fig. 5 are to be understood as being identical with the showing and description given with respect to Figures 1 to 4. The structure likewise presents the symmetrical arrangement and advantages above-recited with the added feature of the heater-ballast being included in the lamp and effective for introducing the desirable heat energy dissipated by the heater-ballast directly in the lamp. It likewise has the added advantage over construction of Fig. 1 in permitting the tubulation 32 to be situated midway of the sides of the press 16.

If preferred, and especially for use in refrigerators where heat transfer is most pronounced by conduction through the base and socket, the heater-ballast element may be situated next the stem. Such arrangement is shown in Fig. 7. In this illustration, we have shown electrode construction and conductor for the far electrode taking the general form shown and described in copending application of coinventer herein, D. D. Knowles, S. N. 339,441, filed June 8, 1940. Stem 13 with press 16, in this view, provide a substantially central supporting rod 39 for a near electrode 40, but without extending through said electrode. An insulative sleeve 41 is situated around the rod between the press and electrode, and on this sleeve is wound a heater-ballast element 42, the far end of which is physically and electrically attached to the electrode whereas the end next the press is made secure to a lead-in connection 43 through the press to the appropriate base connection. Another lead-in connection 44 through the press from the other base 75

terminal part, is connected above the press to a rod or other connection 45 offset from the electrode to make electrical connection with the far electrode (not shown in this view) corresponding to far electrode 11 of Fig. 1.

For initiating discharge in this construction of Fig. 7, a trigger member 46 may be provided effective in operation to obtain a short path from the electrode emitting surface to the trigger member for initiating ionization at load potential. As shown, a branch connection 47 is made from the feeding connection 44 in the stem to a fixed connection 48 protruding from the stem. To this connection 48 is attached the lower end of trigger member 46 which extends upwardly at the side of but spaced from electrode 40, said trigger member being of electrically resistance wire formation and having its far end bent backward into the end opening of the electrode. The spacing of the trigger member in all showings is to be understood as at the minimum break-down voltage distance of the gaseous atmosphere from the electrode with which associated. Furthermore, it is to be understood that the trigger member in this showing, as well as in the preceding views, includes inherent or other resistance sufficient to render passage of current through it and to the electrode by the electron path therebetween more difficult than direct discharge from one electrode to the other after such discharge has begun, thereby automatically stopping current flow by way of the trigger member when glow discharge between the electrodes commences.

It is to be understood that while the showing of Fig. 7 provides for connecting the far electrode by a connection at the outside of the electrode, it is within the scope of the invention to utilize the symmetrical construction of rod connection of Figures 1 to 4 with the heater-resistance element 42 of Fig. 7, and to otherwise combine specific parts of one showing with respect to other specific parts of other views. More generally, therefore, it is to be understood that since the various details of construction, as well as the precise relation and functioning of parts are subject to variation and change without departing from the inventive concept or scope of the invention, all matter contained in the specification or illustrated in the drawing, shall be interpreted as exemplary and not in a limiting sense. It is also intended that the following claims are to be understood as covering all of the generic and specific features of the invention herein shown and described and all statements of the scope of the invention herein set forth as a matter of language which might be said to fall therebetween.

We claim:

1. A discharge lamp comprising an elongated vitreous envelope with a single stem and press, a substantially central rod projecting longitudinally into said envelope from said press, opposed electrodes adjacent opposite ends of the rod, said rod extending axially through both said electrodes, an insulative sleeve on said rod, and a trigger member on said sleeve electrically connected with one electrode and projecting into the other in spaced relation thereto.
2. A discharge lamp comprising an elongated vitreous envelope with stem and press, a substantially central rod projecting longitudinally into said envelope from said press, opposed electrodes adjacent opposite ends of the rod, said rod extending axially through both said elec-

trodes, an insulative sleeve on said rod, and trigger members separate from each other on opposite sides of said sleeve each connected to a different electrode and projecting into the one to which not connected in spaced relation thereto.

3. A discharge lamp comprising an elongated vitreous envelope with stem and press, a substantially central rod projecting longitudinally into said envelope from said press, opposed electrodes adjacent opposite ends of the rod, said rod extending axially through both said electrodes, an insulative sleeve on said rod, and a trigger member comprising a painted-on strip of resistive material on said sleeve electrically connected with one electrode and projecting into the other in spaced relation thereto.

4. A discharge lamp comprising an elongated vitreous envelope with stem and press, a substantially central rod projecting longitudinally into said envelope from said press, opposed electrodes adjacent opposite ends of the rod, said rod extending axially through both said electrodes and having grooves on opposite sides of the said rod, and trigger members in said grooves, each trigger member being connected to an opposite one of said electrodes and projecting into the one to which not connected in spaced relation thereto.

5. A discharge lamp comprising an elongated vitreous envelope with stem and press and enclosing a gaseous atmosphere, a substantially central insulative sleeve projecting longitudinally into said envelope from said press, electrodes in said envelope at separated positions for glow discharge, and a heater-ballast carried by said sleeve and connected to one of said electrodes and at least in part exterior to said electrode for constituting heating means for the gaseous atmosphere in said envelope.

6. A discharge lamp comprising an elongated vitreous envelope with stem and press and enclosing a gaseous atmosphere, a substantially central insulative sleeve projecting longitudinally into said envelope from said press, electrodes in said envelope at separated positions for glow discharge, said sleeve extending from one electrode to the other partly inside and partly outside said electrodes, and a heater-ballast carried longitudinally within and substantially full length of said sleeve and connected

to one of said electrodes and constituting heating means for the gaseous atmosphere in said envelope.

7. A discharge lamp comprising an elongated vitreous envelope with stem and press and enclosing a gaseous atmosphere, a substantially central insulative sleeve projecting longitudinally into said envelope from said press, electrodes in said envelope at separated positions for glow discharge, and a ballast resistance carried around said sleeve between said press and the near electrode, and constituting heating means next the stem end of the envelope for the gaseous atmosphere in said envelope.

8. A discharge lamp comprising an envelope having a stem, a pair of cylindrical glow-discharge electrodes carried by said stem, input and output leads through the stem for said electrodes, a conductive rod mounted in said stem forming a support for both said electrodes and passing through the interior of each longitudinally thereof, said rod being electrically connected to one lead and to the electrode more distant from the stem, whereby glow discharge between the electrodes surrounds the said rod and lateral deflection of the discharge and exterior dark areas along the discharge are avoided.

9. A discharge lamp comprising an elongated envelope having a stem at one end thereof through which all lead-in wires extend into the interior of the envelope, lead-in wires through said stem, a cylindrical cup-shaped electrode at the far end of the envelope from the stem electrically connected to one lead-in wire, another cylindrical cup-shaped electrode at the near end of the envelope to the stem electrically connected to another lead-in wire, and a central rod carried by said stem and extending longitudinally of the envelope, said electrodes being carried by said rod thereby constituting the electrodes, rod and stem a unitary assembly, and said electrodes being spaced from each other with the open ends of the cup shape thereof directed toward each other and receiving the rod therein, whereby glow discharge between the electrodes surrounds the said rod and lateral deflection of the discharge and exterior dark areas along the discharge are avoided.
